(57) **CLAIM**

The ornamental design for a camera bracelet, as shown and described.

DESCRIPTION

FIG. 1 is a front perspective view of a camera bracelet according to a first embodiment of our design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front perspective view of a camera bracelet according to a second embodiment of our design;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.

The broken lines shown in the drawings represent portions of the camera bracelet that form no part of the claimed design.

Stipple-fill areas represent portions of the design that have a color that contrasts with a color of the non-stippled filled areas.
